Primary Examiner — Lauren R Calve

(57) **CLAIM**

The ornamental design for a capsule for mixing multiple substances, as shown and described.

DESCRIPTION

FIG. 1 is a perspective view of a capsule for mixing multiple substances, showing my new design;

FIG. 2 is a top view thereof;

FIG. 3 is a front view thereof;

FIG. 4 is a left side view thereof;

FIG. 5 is a bottom view thereof;

FIG. 6 is a right side view thereof;

FIG. 7 is a rear view thereof; and,

FIG. 8 is a bottom perspective view thereof.

Broken lines in the drawings denote features of the article that are included for the purpose of illustrating context, but form no part of the claimed design.

1 Claim, 8 Drawing Sheets
